UNITED STATES PATENT OFFICE.

JEAN F. WEBB, JR., OF NEW YORK, N. Y., ASSIGNOR TO THE INTERNATIONAL SIGNAL COMPANY, OF NEW YORK, N. Y.

SPEED-CONTROLLED MECHANISM.

1,185,032.

Specification of Letters Patent. Patented May 30, 1916.

Application filed May 15, 1915. Serial No. 28,431.

To all whom it may concern:

Be it known that I, JEAN F. WEBB, Jr., residing at New York, in the county of New York and State of New York, have invented 5 certain new and useful Improvements in Speed-Controlled Mechanism, of which the following is a specification.

My invention relates to the art of train stopping and controlling and it specially 10 has relation to that type of mechanism disclosed in my application filed August 22, 1914, Serial No. 858,094, and that disclosed in the application filed by Jean F. Webb, Sr., and myself October 12, 1914, Serial 15 No. 866,356. The train stopping mechanisms of those applications include means whereby the engineer may reset the operative parts, subject, however, to the action of a speed control that is designed to prohibit such resetting when the train is moving 20 above a predetermined minimum speed.

The present invention relates particularly to the governor for the resetting device and the mechanism for driving the governor 25 from a moving part of the train.

The governor proper herein disclosed, which is also disclosed in my Patent #1,125,419 of Jan. 19, 1915, but, *per se*, is not the invention covered by such patent, 30 consists generally of a rotatable shaft on which a sleeve is provided that is raised and lowered by a centrifugal ball device, a weighted latch being operated by the elevation of the sleeve to engage the notch in the 35 resetting rod when the speed of the train is above a predetermined minimum to hold the rod from movement.

The mechanism by which the governor shaft is driven and which forms one of the 40 essential features of this application, comprises a gear set having a drive connection with the governor spindle and mounted in a box on the governor case or housing, the governor gear set including a driving 45 element that is coupled up with the driving wheel gear set that is in turn carried by a movable support on which the friction drive wheel is also carried.

More subordinately the invention com- 50 prises a friction drive wheel having pro-

vision to permit it to ratchet, or run free, as it were, in the event of the engine drive wheel racing as frequently occurs when a train is started up.

Again, the invention comprises a com- 55 bined governor and speedometer drive whereby the speed at which the governor acts may be indicated.

Again, it is the object of the invention to provide a governor drive which is so con- 60 structed that it can be manufactured at low cost, and in which the parts are designed to occupy a small space only and not interfere with the machinery of the ordinary locomotive to which it is adapted to be 65 attached.

The invention also includes those novel constructions, combinations and arrangements of parts, which will hereinafter be fully described and then be specifically 75 pointed out in the appended claims, reference being had to the accompanying drawings, in which:

Figure 1 is a side elevation showing the invention in use. Fig. 2 is an enlarged elevation of the present invention, the cover of the governor housing being removed. Fig. 3 is a vertical section on the line 3—3 of Fig. 2. Fig. 4 is a side elevation and part section on the line 4—4 on Fig. 5. Fig. 5 80 is a plan view and part section on the line 5—5 of Fig. 4. Fig. 6 is a detail section on the line 6—6 of Fig. 5. Fig. 7 is a plan view of the lower half of the governor gear box with the gears in place. Fig. 8 is a 85 cross section on the line 8—8 of Fig. 2. Fig. 9 is a vertical section on the line 9—9 of Fig. 10. Fig. 10 is a horizontal section on the line 10—10 of Fig. 9.

In the drawings, in which like letters of 90 reference indicate like parts in all of the figures, 13 designates the resetting shaft of the train stopping apparatus by which the engineer may reset the apparatus. Mounted upon suitable brackets 77 at a suitable lo- 95 cation on the locomotive is the governor box or housing 78, which is open at the front and back and designed to be closed by cover plates 79. The housing 78 is vertically bored at 80 at the top and bottom to 100

receive the lug 109 of the gear set at the bottom and a closure plug at the top, although it should be stated that these parts may be reversed in practice, where conditions make it necessary.

81 designates ball races which contain the bearing balls 82 to form a bearing between the housing 78 and the flanged collars 83 that are pinned at 84 to the governor shaft 85. The shaft 85 has key lugs 86 by means of which connection can be made with the driven shaft 110 of the governor gear set. Slidably mounted on the shaft 85 is a sleeve 87 having a slot 88 through which the pin 89 passes, the pin 89 also passing through the shaft 85 and through the ears 90 of the governor balls 91, the ears 92 of which are linked at 93 to the lugs 94 of the sleeve 87.

95 designates guide rods that are mounted 20 in the governor housing 78 and on which the weighted latch 96 is movable up and down to bring its lug 97 into the notch 102 of the resetting rod 13 when the speed of the train is above the predetermined minimum. The 25 weighted latch member 96 is made in two vertical halves which are secured together by screws 101 or in any other suitable way, whereby should one lug 97 break or become injured, the device can be turned around 30 180° and the other lug 97, (see Fig. 3) can be brought into operative position.

98 designates ball race members having bearing balls 99 to afford a ball bearing connection between the sleeve 87 and latch 96, the ball bearing resting upon the flange 100 of the sleeve 87.

The governor gear box is composed of an upper and a lower half section 103—104, separated upon a central horizontal plane 40 and secured together by cap screws 106, four of the screws 106 being of sufficient length to enter the governor housing 78 and secure the gear set thereto while two of the screws are of shorter length to simply hold the governor gear set housing or case sections together, the two sections being provided with pin and pin hole connections 107 to aid in proper matching of the parts when assembling the same.

50 105 designates lugs on the gear case through which the bolts 106 pass.

The case sections 103—104 are provided with bearings 109—108 respectively for the shaft 110 that has a slotted end to receive 55 the lug 86 and make connection with the governor 85, as best shown in Fig. 3 of the drawings. The shaft 110 carries a gear 111 that meshes with a gear 116 on the driven shaft 114 of the governor gear set, the shaft 114 being mounted in bearings 112—113 and having its end 115 secured to a universal joint 117 which is in turn connected to the telescoping shaft that joins the universal joints 117—121. The telescoping shaft, the

purpose of which will be later apparent, 65 comprises an outer sleeve 118, and an inner rod 120 which has a slot 121* and through which the connecting pin 119 is passed, the pin 119 projecting through the hollow shaft or tube 118 and being secured in place by 70 cotter pins or in any other suitable way. The rod section 120 of the shaft is connected with the universal joint 121 that is mounted on the end of the driven shaft 123 of the drive wheel gear set. This shaft 123 75 is mounted in a bearing 124 of the cover 131 of the case 127 of the gear set and in a bearing 125 within the case 127, both bearings 124—125 being bushed by a bearing metal 126, as shown. The case 127 has lugs 128 80 into which the cap screws 130 pass to secure the cover 131 in place.

129 designates pin and hole connections between the cover 131 and the case 127 to assist in matching the parts when assembling the same.

132 is a gear which is secured to the shaft 123 and meshes with a gear 133 on the driving shaft 134, the gear 133 being one element of a double gear, the other element 137 of 90 which is united to the element 133 by a neck 138. The shaft 134 is mounted in bearings 135—136 of the cover 131 and case 127 respectively, the bearings being suitably bushed with bearing metal bushings 126, as 95 shown. The bearing 136 is extended as at 139 to receive the disk portion 157 of the supporting arm 158 to which the case 127 is riveted, as at 122 or rigidly secured in any other suitable manner.

The case 127 is provided with bearings 140—144 in which the speedometer driving shaft 141 is located, the bearing 149 being bushed with a suitable bearing metal bushing 126.

The shaft 141 where it passes through the bearing 144 is provided with a collar 147 that carries a ball race 148 in which the bearing balls 146 are located, the ball race 148 being held in a recess in the cap 149, the cap 110 being secured in place by cap screws 151.

The cap 149 has a threaded neck 150 to which the speedometer shaft casing (which may be of the usual type) 155 is secured.

The shaft 141 has an extension 152 that is 115 slotted at 153 to make connection with the speedometer shaft (not shown).

On a stud 177 carried by a clamp 178 that is secured to a part of the engine frame, is the bearing 156 of the arm 158 that supports the drive wheel 165 and the drive wheel gear set, the arm 158 being formed with the disk 157, hereinbefore referred to.

161 designates an extension that is bored at 162 to receive an adjusting eye bolt 163 125 which is secured to the end of a spring 164, the other end of the spring 164 being fastened to a fixture 160, adjusting nuts 159 be-

ing provided whereby the tension of the spring may be regulated.

The friction wheel 165 may be formed in two sections; one of which 173 may serve as 5 a cover for the other section.

The section 165 of the wheel is provided with inside lugs 166 having recesses to receive the ratchet pins 167 that have collars 168 and are pressed centrally by springs 10 169. The pins 167 having rounded ends 170 to seat in the notches 171 of the ratchet disk 172 which is keyed to the shaft 134, the cover 173 is secured at 174 to the section 165 and both the section 165 and the cover 173 are 15 bored to fit onto shaft 134, washers 175 and lock nuts 176 being provided to hold the wheel on the shaft in practice.

In the operation of the invention when applied to train stopping apparatus, as hereinbefore described, when the train stopping mechanism operates to set the air brakes, if 20 the speed of the train is below a predetermined minimum, the latch lug 97 will not be present in the slot 102 of the resetting rod 13 and therefore the engineer can reset 25 the train stop valve by pulling the rod 13 in any convenient manner. If, however, the speed of the train is such as to be above the predetermined minimum, the latch 97 will 30 be located within the notch 102 and thus prevent reciprocation of the rod 13. Power is transmitted to the governor spindle from the driver wheel of the locomotive through 35 the medium of the driving wheel 165 which has rolling contact with the driver of the locomotive, as best shown in Fig. 1 of the drawings. The wheel 165 is held against the driver wheel by a yieldable support so 40 that any unevenness in the roadbed may be compensated for without disconnecting the wheel 165 from the locomotive driver.

The provision of the telescoping shaft 118-120 provides for any looseness in the engine structure or movements of the support 45 158 so that the governor mechanism may be rigidly mounted by the bracket 77 on the locomotive structure.

From the foregoing description, taken in connection with the accompanying drawings, it is thought the complete construction, 50 operation and advantages of my invention will be readily understood by those skilled in the art.

What I claim is:

55 1. A speed controlled mechanism which includes a housing, a spindle rotatable in said housing, bearings for said spindle, a sleeve slidable on said spindle, governor balls pivoted to said spindle and linked to said sleeve, guides carried by said housing, a weighted latch member mounted on said guides and designed to engage said sleeve whereby as said sleeve is raised, said latch member will be brought into engagement

with said rod, and a driving mechanism 65 coupled to said spindle.

2. A speed controlled mechanism which includes a housing, a spindle rotatable in said housing, bearings for said spindle, a sleeve slidable on said spindle, governor 70 balls pivoted to said spindle and linked to said sleeve, guides carried by said housing, a weighted latch member mounted on said guides and designed to engage said sleeve whereby as said sleeve is raised said latch 75 member will be brought into engagement with said rod, a driving mechanism coupled to said spindle, said latch member comprising a body formed of like sections, fastening devices for holding said sections together, each section including a latching lug, said latch member being adapted to be reversed on said guides to bring either of said lugs into operative relation with said latch. 85

3. In combination with a governor mechanism that includes a housing and operative parts, including a spindle, mounted within said housing; a driving mechanism for said governor, said driving mechanism comprising a drive wheel gear set, a drive wheel carried thereby, said drive wheel gear set including a gear case, a driving shaft, a driven shaft, and transmission gears between said shafts, a governor gear 90 set comprising a gear case secured to said housing, a driving shaft, a driven shaft, and transmission gears between said last named shafts, said governor gear set driven shaft having a coupling engagement with 95 said spindle, and a driving shaft connecting the driven shaft of said drive wheel gear set with the driving shaft of said governor gear set. 100

4. In combination with a governor mechanism that includes a housing and operative parts, including a spindle, mounted within said housing; a driving mechanism for said governor, said driving mechanism comprising a drive wheel gear set, a drive wheel 110 carried thereby, said drive wheel gear set including a gear case, a driving shaft, a driven shaft, and transmission gears between said shafts, a governor gear set comprising a gear case secured to said housing, a driving shaft, a driven shaft, and transmission gears between said last named shafts, said governor gear set driven shaft having a coupling engagement with said spindle, a driving shaft connecting said driven shaft 115 of said drive wheel governor set with the driving shaft of said governor gear set, said driving shaft including extensible sections. 120

5. In combination with a governor mechanism that includes a housing and operative parts, including a spindle, mounted within said housing; a driving mechanism for said

- governor, said driving mechanism comprising a drive wheel gear set, a drive wheel carried thereby, said drive wheel gear set including a gear case, a driving shaft, a driven shaft, and transmission gears between said shafts, a governor gear set comprising a gear case secured to said housing, a driving shaft, a driven shaft, and transmission gears between said last named shafts, said governor gear set driven shaft having a coupling engagement with said spindle, a driving shaft connecting the driven shaft of said drive wheel gear set with the driving shaft of said governor gear set, said driving shaft including extensible sections, and universal joints connecting said driving shaft to said driven shaft of said drive wheel gear set and to said driving shaft of said governor gear set.
6. In combination with a governor mechanism that includes a housing and operative parts, including a spindle, mounted within said housing; a driving mechanism for said governor, said driving mechanism comprising a drive wheel gear set, a drive wheel carried thereby, said drive wheel gear set including a gear case, a driving shaft, a driven shaft, and transmission gears between said shafts, a governor gear set comprising a gear case secured to said housing, a driving shaft, a driven shaft, and transmission gears between said last named shafts, said governor gear set driven shaft having a coupling engagement with said spindle, a driving shaft connecting the driven shaft of said drive wheel gear set with the driving shaft of said governor gear set, said driving shaft including extensible sections, universal joints connecting said driving shaft to said driven shaft of said drive wheel gear set and to said driving shaft of said governor gear set, said driving shaft including extensible sections.
7. In a speed controlling mechanism, a governor including a housing and governor mechanism within said housing, said governor mechanism including a spindle; a support; a drive wheel and a drive wheel gear set mounted on said support; a governor gear set mounted on said housing; and a transmission shaft between said gear sets, said transmission shaft comprising telescoping sections.
8. In a speed controlling mechanism, a governor including a housing and governor mechanism within said housing, said governor mechanism including a spindle; a support; a drive wheel and a drive wheel gear set mounted on said support; a governor gear set mounted on said housing; a transmission shaft between said gear sets, said transmission shaft comprising telescoping sections, and universal joints for connecting said transmission shaft with the respective gear sets.

9. In a speed controlling mechanism, a governor including a housing and governor mechanism within said housing, said governor mechanism including a spindle; a support; a drive wheel and a drive wheel gear set mounted on said support; a governor gear set mounted on said housing; a transmission shaft between said gear sets, a speedometer, and a driving shaft for said speedometer connected with said driving wheel gear set.

10. In combination with the speed controlled rod of a train stopping apparatus and the driver of a locomotive; a governor and a friction driving mechanism for said governor, said driving mechanism comprising a driving wheel designed to run in contact with the engine driver, a support for said wheel, a gear set including a driving shaft mounted on said support, said driving wheel being mounted on said driving shaft, said drive wheel gear set also including power transmitting elements, a governor gear set including a driving shaft and power transmitting elements, a driving connection between said gear sets, and yieldable connection between said drive wheel and the shaft on which it is mounted.

11. In combination with the speed controlled rod of a train stopping apparatus and the driver of a locomotive; a governor and a friction driving mechanism for said governor, said driving mechanism comprising a driving wheel designed to run in contact with the engine driver, a support for said wheel, a gear set including a driving shaft mounted on said support, said driving wheel being mounted on said driving shaft, said drive wheel gear set also including power transmitting elements, a governor gear set including a driving shaft and power transmitting elements, a driving connection between said gear sets, and a ratchet connection between said drive wheel and the shaft on which the same is mounted.

12. In a drive mechanism for speed controlled apparatus, a drive wheel gear set comprising a casing having a plurality of sets of shaft bearings, a drive shaft mounted in one set of said bearings, a driven shaft mounted in another set of bearings, gear connections between said drive shaft and said driven shaft, a drive wheel mounted on said drive shaft, a support for the aforesaid structure to maintain said drive wheel in rolling contact with the prime mover, a second driven shaft mounted in a third set of bearings in said gear casing, and gear connections between said driving shaft and said second driven shaft.

13. In a mechanism of the character described, a gear case having a set of driving shaft bearings, said gear case including a receptacle and a cover therefor, a support for said gear case, a driving shaft mounted

in said driving shaft bearings, a driving wheel on said driving shaft outside of said casing, said gear case having a second set of bearings, a driven shaft in said second set of bearings, gears on said shafts meshing with each other, said gear case having a third set of bearings extending in a direction at right angles to the plane containing said driving shaft and said first mentioned

driven shaft, a second driven shaft mounted 10 in said third set of bearings, gears connecting said driving shaft with said third shaft, said case having an extension, a cap secured on said extension, anti-friction bearings for said third shaft adjacent to said 15 cap, said cap having a coupling neck and said third shaft having a coupling slot.
